UNITED STATES PATENT OFFICE.

WILLIAM A. HELD, OF FREEPORT, ILLINOIS, ASSIGNOR TO W. A. HELD COMPANY, OF FREEPORT, ILLINOIS, A CORPORATION OF ILLINOIS.

DESIGN FOR A BIRD-FEEDING STATION.

Application filed March 10, 1926. Serial No. 16,856. Term of patent 3½ years.

To all whom it may concern:

Be it known that I, WILLIAM A. HELD, a citizen of the United States, residing at Freeport, in the county of Stephenson and State of Illinois, have invented a new, original, and ornamental Design for Bird-Feeding Stations, of which the following is a specification, reference being had to the ac-

companying drawing, forming a part thereof.

The drawing is a perspective view of the article showing my new design.

I claim:

The ornamental design for a bird-feeding station, as shown.

WILLIAM A. HELD.
